United States Patent Office

Des. 208,673
Patented Sept. 19, 1967

208,673

BEVERAGE BOTTLE CASE

Heinz W. Adomat, Kielmannseggstrasse 71, 2,
Hamburg 70, Germany

Filed Dec. 1, 1966, Ser. No. 4,891

Term of patent 14 years

(Cl. D58--5)

Design 3

Design 2

I claim:

The ornamental design for a beverage bottle case, substantially as shown and described.
